UNITED STATES PATENT OFFICE

2,671,234

ROTARY TOOTHBRUSH WITH CONTINUOUS
LIP GUARD

Donald P. Grover, Chicago, Ill.

Application November 3, 1950, Serial No. 193,842

4 Claims. (Cl. 15—23)

1

This invention relates in general to rotary toothbrushes adapted to be operated by a source of electrical energy or other means of rotation and, particularly, to a type of rotary toothbrush adapted for personal use as distinguished from those commonly used by dentists. The present application is a continuation-in-part of my co-pending application, Serial No. 692,270, filed August 22, 1946, now Patent No. 2,533,108.

Various forms of electrically driven rotary toothbrushes have been developed heretofore, but have found very little favor with the public in general. One of the disadvantages of the early type of rotary toothbrush was the absence of any shield partially surrounding the brush element, thus causing some of the toothpaste on the brush to be thrown off and splattered about during the rotation of the brush and permitting the brush to contact the soft inner portions of the mouth causing irritation thereof.

A later development introduced a shield which extended lengthwise of and partially surrounded the rotating brush element to prevent such splattering and mouth irritation. However, actual usage of this type of brush proved unsatisfactory because of the tendency of the lip and/or soft fleshy mouth parts of the user to be drawn inwardly against the bristles of the brush and between the bristles and the edge of the shield when the brush was placed against the teeth.

I have been able to overcome the disadvantages of these earlier types of rotary toothbrushes in my present invention, the principal object of which is to provide a power driven rotary toothbrush having novel guard means to prevent the lip and soft fleshy mouth parts of the user from being pulled or drawn inwardly against the bristles of the brush element and being lacerated thereby during rotation thereof.

Another object of the invention is to provide a rotary toothbrush having a plurality of spaced guards along the length of the brush element and extending between the bristles thereon whereby the lip and soft fleshy mouth parts of the user is prevented from being pulled or drawn inwardly against the brush during rotation thereof.

A further object is to provide a rotary toothbrush having a shield thereon wherein lip guards in the form of thin wire members are located adjacent the brush element to thereby prevent the lip and soft fleshy mouth parts of the user from being drawn inwardly between the brush and the shield, thereby causing irritation or laceration.

2

Still another object is to provide a rotary toothbrush wherein a series of coiled wire members is spaced throughout the length of the brush element adjacent thereto whereby the lip or soft fleshy mouth portions of a user are prevented from being drawn inwardly against the brush.

A still further object is to provide a lip guard for a rotary toothbrush which consists of a single coil of wire extending lengthwise of the brush element and having one end thereof secured to the handle portion whereby the outer edges of the coiled wire will prevent the lip or soft fleshy mouth portions of a user from being irritated or lacerated by the brush.

Other objects and advantages of the invention will become apparent upon a reading of the following description taken in conjunction with the accompanying drawing in which:

Fig. 1 is a side elevational view of a rotary toothbrush embodying the present invention;

Fig. 2 is an end elevational view thereof; and

Fig. 3 is a perspective view thereof with the brush element removed.

Briefly described, the invention herein consists primarily in the provision of guard means against which the lip of the user of the rotary toothbrush will ordinarily bear during the use thereof to guide or direct the lip to the outer side of the shield and thus prevent the lip from being drawn inwardly between the brush element and the shield. When the rotary brush is in use and placed against the teeth the brush element is usually designed to rotate in a manner to brush the teeth away from the gums, which is considered by dentists as the proper way to brush teeth. In actual practice where no lip guards are present, it has been found that brushes of this character disclosed in the prior art have a tendency to pull the lip inwardly against the bristles of the brush, and if a shield is present the tendency is to pull the lip between the brush and the edge of the shield. Serious injury to the lip may not necessarily result, but such an experience is decidedly unsatisfactory and unpleasant, discourages further use of the device by causing rawness and bleeding of the lip and has been considered the principal reason for the lack of commercial success of earlier rotary toothbrushes.

It will be evident that many specific forms of guard means may be designed to accomplish the main purpose of this invention, for example, such as those disclosed in my earlier filed co-pending applications, Serial No. 691,273, filed August 17, 1946, now Patent No. 2,533,106, issued December

5, 1950, Serial No. 691,979, filed August 21, 1946, now Patent No. 2,533,107, issued December 5, 1950, and Serial No. 692,270, filed August 22, 1946, now Patent No. 2,533,108, issued December 5, 1950.

In order further to distinguish the forms of the invention disclosed herein from those illustrated and described in my above referred to co-pending applications, the lip guard herein is preferably formed of wire and constitutes a continuous coil extending outwardly from one end of the handle portion. The term wire as used herein is not intended to limit the invention to steel, or other metallic forms of wire, as this term is commonly understood since the wire may be formed of thin extruded plastic material, or any other material which may be suitable for this purpose.

The driving means for rotating the brush element may embody an electric motor or other driving means enclosed within the handle portion, or it may comprise a flexible shaft adapted to be connected to the rear end of the handle portion to drive a rotatable shaft within the handle to which the brush element is connected, as more specifically described in my above referred to co-pending applications. The specific form of my invention is unimportant since the invention is directed to the form of lip guards which prevents the lip from being drawn against the rotating brush element, or from being drawn inwardly between the brush and some adjacent form of supporting means.

The present invention embodies a handle member 1 having a suitable form of rotatable shaft therein, as described in my above referred to co-pending applications. The forward end of the rotatable shaft within the handle 1 may be so constructed as to receive the spindle 2 of a brush element 3 so as to rotate the brush when the shaft is rotated.

A continuous single coil of wire 4 is provided and may be secured at one end 5 thereof directly to the forward end 6 of the handle 1. The forward end 7 of coil 4 may be attached to the forward end of spindle 2 of the brush element, whereupon the coil and spindle may mutually support each other. The single coil of wire will extend lengthwise of the brush element and will preferably, although not necessarily, surround the spindle, as shown in Fig. 1.

The spaces 8 between the individual coils will permit passage of the brush bristles therethrough for cleaning the teeth and the curved surfaces of the coil on each side of the element will act as guard means preventing the lip of the user from being drawn inwardly between the bristles of the brush 3, and the shield 9.

The invention is disclosed herein as being used in combination with a solid shield to prevent splattering of toothpaste, if desired however, this shield may be entirely dispensed with because the coil of wire itself extends below the brush element and may have some shielding effect. The fact that the coil extends below the brush element also enables it to act as a guard and prevent the bristles from contacting the inner soft portions of the mouth when that side of the brush is exposed thereto.

When it is desired to remove the brush element for replacement or cleaning, it is merely necessary to disconnect the forward end of the brush spindle 2 from the end 7 of the coil or wire at which time it can be merely lifted out.

From the foregoing description it will be ap-

parent that the present device embodies certain novel forms of lip guards for use in connection with rotary toothbrushes, all of which will effectively prevent injury to the lip and fleshy portions of the mouth of a user. As stated previously, the brush is intended to be used in such a way that rotation of the brush element is away from the gums. If the toothbrush is constructed so that the brush element always rotates in the same direction, then the lip guard in any case may be located on only one side thereof. Thus, the lip guards disclosed herein may be dispensed with along one side of the brush element without departing in any way from the spirit of the invention. The provision of lip guards along both sides of the rotating brush element may be necessary, however, if suitable mechanism is provided to reverse the direction of rotation of the brush.

It will be evident that as the brush rotates against the teeth, any tendency to draw the lip or other fleshy portions of the mouth inwardly between the brush and the shield will be effectively prevented by the curvature of the coil on each side of the brush which tend to guide the lip outwardly and downwardly and away from the brush bristles. It will, therefore, be evident that I have provided a novel improvement in lip guards for use on rotary toothbrushes wherein the lip of a user is prevented from being drawn inwardly against the brush during rotation thereof.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. A rotary toothbrush of the class described, comprising a handle portion, a brush element rotatably mounted at one end of said handle portion, a shield mounted on said handle portion adjacent said brush element, and a single series of spaced coils of wire extending lengthwise of and adjacent said brush element with portions thereof between the peripheral surface of the brush element and the edges of said shield thereby forming a guard to prevent the lip or fleshy mouth parts of a user from being drawn between said brush element and shield during rotation thereof.

2. A rotary toothbrush of the class described, comprising a handle portion, a brush element rotatably mounted at one end of said handle portion, a shield mounted on said handle portion adjacent said brush element, and a single continuous coil of wire extending lengthwise of said brush element and secured at one end thereof to said handle portion, said coil of wire having portions thereof between the peripheral surface of said brush element at both sides thereof and the adjacent sides of said shield thereby to prevent the lip or fleshy mouth parts of a user from being drawn between said brush element and shield during rotation thereof.

3. A rotary toothbrush of the class described, comprising a handle portion, a brush element rotatably mounted at one end of said handle portion having a spindle to support the bristles thereof, a shield mounted on said handle portion adjacent said brush element, and a single continuous coil of wire extending lengthwise of said brush element, one end thereof being secured to

said handle portion and the other end thereof supporting the outer end of said spindle, said coil of wire having portions thereof between the peripheral surface of said brush element and said shield whereby the lip or other fleshy mouth parts of a user is prevented from being drawn between said brush element and shield during rotation thereof.

4. A rotary toothbrush of the class described, comprising a handle portion, a brush element 10 rotatably mounted at one end of said handle portion having a spindle to support the bristles thereof, a shield mounted on said handle portion adjacent said brush element, and a single continuous coil of wire extending lengthwise of said 15 brush element and surrounding said spindle and having portions thereof positioned between the periphery of said brush element and the edges of

6
said shield, whereby the lip or other fleshy mouth parts of a user is prevented from being drawn between said brush element and shield during rotation thereof.

DONALD P. GROVER.
